UNITED STATES PATENT OFFICE.

FRANK W. SCHWINN, OF CHICAGO, ILLINOIS.

KICK-STARTER MECHANISM.

1,268,501.

Specification of Letters Patent. Patented June 4, 1918.

Application filed February 6, 1918. Serial No. 215,596.

To all whom it may concern:

Be it known that I, FRANK W. SCHWINN, a citizen of the United States, residing at Chicago, in the county of Cook and State of Illinois, have invented a new and useful Kick- Starter Mechanism, of which the following is a specification.

My invention relates to improvements in starting mechanism for internal combustion engines and is particularly directed to so-called "kick-starters" commonly employed on motorcycles and including a train of gearing connected with the motor and actuated by a pedal-crank which is kicked 10 or pushed suddenly with considerable force 15 by the foot to cause the motor to be rapidly turned over for starting purposes.

My invention will be fully understood from the following specification, taken in 20 connection with the accompanying drawings, in which—

Figure 1 is a fragmentary side elevation of the lower portion of a typical motorcycle frame showing the mounting of the 25 starting-gear train therein; Fig. 2 is an enlarged longitudinal central section through the starter-gear, showing the manner of mounting the same upon its shaft; Fig. 3 is an enlarged face view of the outer 30 toothed annulus of the gear of my invention; Fig. 4 is a similar view of the hub portion of the gear showing the cushioning spring in position; Fig. 5 is an edge view of the hub portion shown in Fig. 4; and 35 Fig. 6 is a rear face view of the same.

For a more complete illustration of the motorcycle fragmentarily illustrated in these drawings, reference may be had to my prior Patent No. 1,215,877, of February 13, 1917.

Referring more particularly to the accompanying drawings, the numeral 10 designates the crank-case of the internal combustion motor and the numeral 11, a starter-shaft suitably journaled adjacent the motor 40 and connected with the crank-shaft thereof by suitable gearing.

Back of and parallel with the starter-shaft 11 there is journaled a pedal-shaft 12 carrying upon one end a pedal-crank 13 and 50 upon the other a sector-gear 14, which is adapted to mesh with and drive a gear upon the starter-shaft 11 and thus to transmit motion to the crank-shaft. It has hitherto been the practice to apply a standard one- 55 piece gear to the starter-shaft 11. It has

been found in practice, however, that the motor would frequently come to a stop in such position as to cause the teeth of the sector-gear 14 to wedge against the top of the teeth of the gear upon the starter-shaft, 60 instead of properly meshing therewith. Under these conditions the relatively great force applied by the weight of the operator on the pedal-crank 13 coming with great suddenness, as a kick or shock upon the 65 parts, is sufficient in many instances to break the gears, spring the shafts, or even to cause a fracture of the cast frame or casing in which they are supported.

It is the particular end and aim of the 70 present invention to avoid this difficulty by modifying the construction of the starter-gear in such a way as to make it impossible for this wedging action to occur and to insure a proper meshing of the gear and sec- 75 tor under all conditions.

In general this object is accomplished by the provision of a two-piece gear embodying a central hub section connected with the 80 starter-shaft and an outer annulus carrying the gear teeth and adapted to be engaged by the sector-gear 14, the outer annulus and the central hub having a limited independent movement under the restraining force of a spring. The central or hub portion referred to is illustrated in Figs. 4, 5 and 6, and is designated 15. Upon one face of the 85 same there are formed ratchet-teeth 16, which in the assembled position of the parts coöperate with complementary teeth formed in the opposed face of a collar or sleeve 17 on the starter-shaft 11. On the opposite face of the hub portion there is a groove 18 which receives a ratchet-engaging spring, as will 90 later appear.

In the periphery of the hub portion 15 there is milled an undercut keyway 19, in which there is seated a key 20 of the cross-section shown in Figs. 4 and 6.

The outer toothed annulus is designated 21 and is bored to a diameter slightly less than the diameter of the hub portion 15 and then counterbored to a diameter equal to that of the latter, thus providing a shoulder 22 against which the grooved face of the hub seats in the assembled position of the parts, as shown in Fig. 2. To receive the key 20 the toothed annulus is provided with a rectangular keyway 23, of a width 105 somewhat greater than that of the key, so 110

as to admit of a relative angular movement of the hub and annulus approximately equal to the angular interval of one tooth of the gear. The inclination of the side faces of the key 20 is such that these faces usually bear respectively over their entire surface upon the faces of the keyway 23. In the assembled position of the parts the hub portion 15 and the toothed annulus 21 are connected by a spring in the form of a wire loop 24 having out-turned ends which engage, respectively, in the key 20 and in the body of the toothed annulus. For assembling the two parts of the starter-gear to make the latter a unitary structure, there is provided an annular face-plate 25, which is secured to the counterbored face of the toothed annulus as by the screws 26 and serves to retain the hub portion in its place 20 within the counterbore.

In assembling the structure, the compound or two-piece starter-gear is mounted upon the starter-shaft 11, as shown in Fig. 2, the ratchet-teeth 16 of the hub portion 25 engaging the complementary teeth on the collar 17. The ratchet teeth are normally held in this engaging relationship by a small coil-spring 27 confined between the groove 18 in the face of the hub portion 80 and a nut 28 on the end of the starter-shaft. This nut is locked in position by a flanged cover-plate 29 fastened to the end of the starter-shaft by a screw 30.

The operation of the mechanism described 35 is as follows: The collar 17, being connected by suitable mechanism with the crank-shaft of the internal combustion engine (either through the starter-shaft 11 or otherwise) and the parts being in the position shown 40 in Figs. 1 and 2, the pedal-crank 13 may be operated in the usual way to rock the shaft 12 and cause the sector-gear 14 to engage the teeth of the annulus 21. In place of meeting the full load of the motor, immediately upon engaging its teeth with the teeth 45 of the annulus 21 the sector-gear 14 meets only the load of the spring 24, which is relatively light, until the annular gear has been turned through approximately the angular distance of one tooth, corresponding 50 to the clearance between the key 20 and the keyway 23. By reason of this relatively negligible initial load, the sector-gear is enabled to mesh perfectly with the teeth of 55 the annular gear. If, for example, the parts have been stopped in such position as to cause any wedging tendency, the annulus 21 may slip forward a sufficient distance 60 to destroy the wedging action and bring the teeth into perfect mesh, before the clearance between the key and keyway is taken up. When this clearance has once been taken up the two-piece starter-gear acts as a unitary gear and is driven forward by the 65 sector-gear 14 to turn the crank-shaft of

the internal combustion engine and start the same. When the engine has started the ratchet-teeth 16 automatically free themselves, the spring 27 yielding to permit the starter-gear to be forced outwardly on its 70 shaft. The shaft will therefore now overrun the gear, and the pedal-crank may be returned to its initial position, driving the starter-gear backwardly. When the parts are again brought to the position shown in 75 Fig. 1 the spring 27 forces the ratchet teeth again into engagement and the shaft 11 and the gear thereon turn as a unit, thereby obviating the continuous operation of the ratchet over-run device. As soon as the 80 starting load is removed from the annulus 21 the spring 24 thereof again takes up the clearance between the key 20 and the keyway 23 in the reverse direction, so that upon any subsequent actuation of the starting mechanism the toothed annulus will 85 again be free to rotate independently in its hub through the limited distance required to insure perfect meshing of the teeth.

Due to the undercut construction of the 90 keyway 19, the key 20 therein is by the action of centrifugal force held firmly against the walls of the keyway.

By the construction described the difficulties heretofore met with in the operation of 95 key-starters have been entirely overcome.

While I have shown and described in considerable detail one specific embodiment of my invention it will be understood that this is illustrative only and for the purpose of 100 making the invention more clear, and that I do not regard the invention as limited to these details nor to any of them, except in so far as such limitations are included within the terms of the accompanying 105 claims, in which it is my intention to claim all novelty inherent in my invention as broadly as is permissible in view of the prior art.

What I regard as new and desire to secure by Letters Patent is:

1. In mechanism of the class described, the combination with a sector-gear of a starter-gear with which the same is adapted to mesh and comprising a toothed member and a power-transmitting member, the toothed member having a limited movement in the direction of its normal action independently of the power-transmitting member, whereby engagement of the sector-gear 115 with the toothed member may be effected before the latter assumes its load.

2. In mechanism of the class described, the combination with a sector-gear of a starter-gear with which the former is adapted to mesh, said starter-gear comprising a toothed member and a power-transmitting member having limited independent angular movement, and a spring resisting such movement in the direction of the normal actua- 120 125 130

tion of the starter-gear, whereby the sector-gear may be meshed with the starter-gear under the resistance of the said spring only.

3. In mechanism of the class described, 5 the combination with a sector-gear of a starter-gear with which the former is adapted to mesh and comprising an outer toothed annulus, and an inner hub portion having a limited angular movement with reference 10 thereto, said hub member serving as a power transmission element of the starter-gear.

4. In mechanism of the class described, 15 the combination with a sector-gear, of a starter-gear comprising an outer-toothed annulus with which the sector-gear is adapted to mesh, a hub portion independently rotatable with respect to the outer toothed

annulus, a key secured to one of said members and coöperating with a keyway of greater angular width than the other of said 20 members, and a spring connecting said members and yieldingly taking up the lost motion between them.

5. A starter-gear comprising an outer toothed annulus, a central hub portion having a bearing in the annulus for movement therein, a key secured to one of said members and coöperating with a keyway of greater 25 angular width than the other member, and a spring connecting the said members and 30 yieldingly taking up the lost motion between them.

FRANK W. SCHWINN.
